The ornamental design for a die-cut blank for combined display card and easel, as shown and described.

DESCRIPTION

FIG. 1 is a front elevational view of the die-cut blank for combined display card and easel showing my new design, the rear view being a mirror image;

FIG. 2 is a top edge view of the blank of FIG. 1;

FIG. 3 is a bottom edge view of the blank of FIGS. 1 and 2;

FIG. 4 is a left edge view of the blank of FIGS. 1-3, and, FIG. 5 is a right edge view of the blank of FIGS. 1-4.

The broken lines shown on FIG. 1 represent fold lines.
